[57] ABSTRACT

A pair of U-shaped spring bands pivoted together with a longitudinal pivot and connected by a chain along one side. The spring bands engage the crossed wrists of the user causing him to use his hands oppositely from normal when performing such things as bouncing and catching a ball, catching a balloon, lacing and tieing shoes, writing names, folding and ripping paper, threading needles, and the like.

TOY SHACKLES

BACKGROUND OF THE INVENTION

1. Field of the Invention

The present invention relates to toys and particularly to toy shackles.

2. Summary of the Invention

A pair of U-shaped spring bands are pivoted together by a longitudinal pivot and connected by a chain extending therebetween. The bands engage over the crossed wrists of the user causing him to approach each use of his hands from a different relationship.

The primary object of the invention is to provide toy shackles which create fun and humor in the use of the hands.

Other objects and advantages will become apparent in the following specification when considered in the light of the attached drawings.

BRIEF DESCRIPTION OF THE DRAWINGS

FIG. 1 is a perspective view of the invention shown attached to the wrists of a user;

FIG. 2 is a top plan view of the invention;

FIG. 3 is a side elevation of the invention; and

FIG. 4 is a fragmentary vertical cross-section taken along the line 4-4 of FIG. 2, looking in the direction of the arrows.

DESCRIPTION OF THE PREFERRED EMBODIMENT

Referring now to the drawings in detail wherein like reference characters indicate like parts throughout the several figures the reference numeral 10 indicates generally toy shackles constructed in accordance with the invention.

The toy shackles 10 include a generally U-shaped spring band 11 and an identical generally U-shaped spring band 12. The spring band 11 has a pair of arcuate side walls 13, 14 connected by a generally flat bight 15. The side wall 13 has an outwardly flared extension 16 and the side wall 14 has an outwardly flared extension 17. The band 12 is identical to the

band 11 and the bight 15 thereof is engaged with the bight 15 of the band 11 with the bights 15 secured together by a pivot pin 18 extending longitudinally therethrough.

A light chain 19 extends from the side wall 14 of the band 11 to the side wall 14 of the band 12 and is secured thereto by a cotterkey 20 at each end extending through the side wall 14.

In the use and operation of the invention the band 11 is slipped over one wrist of the user and the band 12 is slipped over the other wrist of the user with the wrists in crossed position (as illustrated in FIG. 1). In this position humorous efforts are made to perform normal activities while retaining the toy shackles in place. Some of these activities would include bouncing and catching a ball, catching a balloon, lacing and tying shoes, writing, folding and ripping paper, threading needles, unscrewing a fruit jar lid, and many other activities devised by the users.

Obviously the arms and hands are in effect upside down facing outwards so that each of the activities requires the participant to act contrary to the norm in order to accomplish the activity.

Having thus described the preferred embodiment of the invention it should be understood that numerous structural modifications and adaptations may be resorted to without departing from the spirit of the invention.

What is claimed is:

1. Toy shackles comprising a pair of generally U-shaped spring bands for engagement over the crossed wrists of the user, each of said U-shaped spring bands including a pair of arcuate side walls arranged in spaced apart confronting relation and a relatively flat bight integrally connecting said side walls at one end thereof, a pivot pin extending centrally through the bight of said band to pivotally secure said bands together, with said bands having relative motion with respect to each other only about said pivot pin, and flexible means connected at its opposite ends to one side wall of each of said bands at a point thereon remote from said bight to limit the pivotal movement of said bands about said pivot pin. * * * *
